CLAIM

The ornamental design for an animal ear tag, as shown and described.

DESCRIPTION

FIG. 1 is a front perspective view of an animal ear tag showing our new design;

FIG. 2 is a front view thereof;

FIG. 3 is a rear view thereof;

FIG. 4 is a right side view thereof; The left side view is a mirror image of the right side view thereof;

FIG. 5 is a top view thereof; and,

FIG. 6 is a bottom view thereof.
